UNITED STATES PATENT OFFICE

168,444

GAME BOARD

Satolli F. Glassmeyer, Forest Hills, Ky.

Application August 2, 1952, Serial No. 20,884

Term of patent 7 years

(Cl. D34—5)

To all whom it may concern:

Be it known that I, Satolli F. Glassmeyer, a citizen of the United States and a resident of Forest Hills, in the county of Kenton and the State of Kentucky, have invented a new, original, and ornamental Design for a Game Board, of which the following is a specification, reference being made to the accompanying drawing, forming a part thereof.

Fig. 1 is a top plan view of my new design for a game board.

Fig. 2 is a side elevational view of the game board shown in Fig. 1.

I claim:

The ornamental design for a game board, as shown.

SATOLLI F. GLASSMEYER.
